BALL

William A. Whittaker, Dobbs Ferry, N. Y.

Application February 26, 1948, Serial No. 144,740

Term of patent 14 years

(Cl. D34—15)

To all whom it may concern:

Be it known that I, William A. Whittaker, a citizen of the United States, residing at Judson Avenue, Dobbs Ferry, county of Westchester, State of New York, have invented a new, original, and ornamental Design for a Ball, of which the following is a specification, reference being had to the accompanying drawing, forming part thereof.

Fig. 1 is a face view of the ball, showing my new design;

Fig. 2 is a face view thereof looking in the direction of the arrow 2 in Fig. 1, and

Fig. 3 is a cross-sectional view thereof taken substantially along line 3—3 in Fig. 2.

The drawing figures are shaded to indicate transparency.

I claim:

The ornamental design for a ball, substantially as shown and described.

WILLIAM A. WHITTAKER.
